HARRY F. SCHWARTZENBERG, OF CHICAGO, ILLINOIS, ASSIGNOR TO WILLIAM H. MINER, OF CHICAGO, ILLINOIS.

DRAFT-RIGGING FOR RAILWAY-CARS.

1,146,286.

Specification of Letters Patent. Patented July 13, 1915.

Application filed March 9, 1914. Serial No. 823,282.

To all whom it may concern:

Be it known that I, HARRY F. SCHWARTZENBERG, a citizen of the United States, residing at Chicago, in the county of Cook and 5 State of Illinois, have invented a certain new and useful Improvement in Draft-Rigging for Railway-Cars, of which the following is a full, clear, concise, and exact description, reference being had to the accompanying drawings, forming a part of this 10 specification.

My invention relates to improvements in draft yokes for railway car draft rigging.

The object of my invention is to provide a 15 draft yoke of simple and strong construction.

In the drawings forming a part of this specification, Figure 1, is a plan view of a draft yoke embodying my invention. Fig. 2, is a side elevation partly in vertical longitudinal section, with the butt and rear portion of the shank of a draw bar shown in dotted lines. Fig. 3 is a cross section on line 3—3 of Fig. 2. Fig. 4 is a cross section 20 on line 4—4 of Fig. 2. Fig. 5 is a rear end view of the yoke.

Referring to the drawings the numerals 6 and 7 represent the upper and lower limbs respectively of the draft yoke, 8—8 detachable connecting plates, 9 the intermediate yoke thimble, 10 the rear yoke thimble, 11 the shank of the draw bar and 12 the draw bar butt, the rear portion of the draw bar only being shown by the dotted lines in Fig. 35 2 of the drawings.

The detachable connecting plates 8, are arranged one on either side of the draw bar, each having a transverse slot, 13, registering with the slot 14, through the draw bar to 40 receive the coupler key 15, shown in dotted lines in Fig. 3 of the drawings. Each plate is provided with upper and lower transverse slots 16 and 17 respectively, registering with the upper and lower transverse slots 18 and 45 19 respectively through the forward ends of the limbs 6 and 7 of the yoke. The slot 18 in the upper limb 6 is disposed through a preferably enlarged forward portion 20 of said limb and likewise the slot 19 in the lower limb 7 preferably passes through an enlarged forward portion 21, of the lower limb. At their forward ends each of the yoke limbs is provided with an inturned gib adapted to engage the oppositely arranged 50 shoulders 22—22 with which the ordinary

draw bar is provided—upper and lower front yoke keys 23 and 24 respectively passing through registering slots in the plates 8, and the forward ends of the limbs of the yoke secure said members together. Suitable means, preferably the cotter pins 25—25, are employed to secure the keys 23 and 24 within their respective slots, each plate 8, being preferably provided both at the top and bottom of its outer face with an offset portion or shoulder 26, having a perforation 27 registering with a suitable perforation 28 in the inclosed yoke key for the passage of a cotter pin 25.

The intermediate thimble 9, is a cored H shaped member having upper and lower outwardly opening grooves, 29 and 30 respectively, to receive respectively the upper limb 6 and the lower limb 7 of the yoke longitudinally therein. The said thimble 9 is preferably laterally provided with upper and lower offset portions or shoulders 31—31, and upper transverse perforations 33 for the passage respectively of the upper intermediate yoke key 34, and the lower intermediate yoke key 35. The upper key 34 passes through a slot 36 in the upper limb 6 entering preferably through the enlarged portion 37 thereof. The lower key 35 passes through a transverse slot 38 in the lower limb 7, preferably provided through the enlarged portion 39 thereof. The intermediate yoke keys are secured against accidental displacement by the cotter pins 40—40, passing preferably through alined perforations 41 in the shoulders 31, and the inclosed key. The intermediate thimble 9 is preferably formed by the lateral plates 41—41 connected between the limbs of the yoke by the preferably integral upper and lower cross pieces 42 and 43, respectively and by the front and rear preferably integral plates 44 and 45 respectively, each of the last mentioned plates being provided with the cored opening 46. The upper and lower cross pieces 42 and 43, form respectively the bed of the upper groove 29 and of the lower groove 30.

The rear thimble 10 is preferably a rearwardly opening hollow member formed by the side plates 47—47, the preferably integral upper and lower cross members 48 and 49 respectively, and the front preferably integral plate 50, the thimble being H shaped in cross section and having an upper out-

wardly opening groove 51 to receive the upper limb 6 of the yoke and a lower outwardly opening groove 52 to receive the yoke's lower limb 7.

5 The side plates 47 each are furnished with upper and lower transverse slots 53 and 54 respectively alined respectively with the transverse slot 55 in the upper limb 6 of the yoke and the slot 56 in the lower limb of the 10 yoke, the upper slots to receive the upper rear yoke key 57 and the lower ones to receive the lower rear yoke key 58.

At their rear ends the limbs 6 and 7 of the yoke are each provided with an inturned 15 gib 59 to engage an adjacent shoulder 60 with which the rear yoke thimble 10 is rearwardly provided.

In preferable construction the rear thimble 10 is provided with the internal vertical 20 longitudinal preferably integral strengthening rib 61. The rear yoke keys 57 and 58 are provided with the perforations 62—62 each to receive a cotter pin 63 passing through alined openings 64 in an offset 25 portion or shoulder with which the rear thimble 10 is in preferable construction provided at the upper and lower portion of each outer lateral face.

The particular form of my invention illustrated in the drawings is a yoke adapted for 30 tandem arranged draft gear.

I claim—

1. In a draft yoke for railway car draft rigging in combination, a pair of limbs, 35 transversely extending keys and a connecting thimble, the thimble having upper and lower outwardly opening grooves to receive the limbs, the keys extending across said grooves and securing the limbs therewithin.

40 2. In a draft yoke for railway car draft rigging in combination, a pair of limbs, a connecting thimble having outwardly opening grooves to receive the limbs, and a key for each of said limbs—the thimble having 45 transverse slots to receive the keys.

3. In a draft yoke for railway car draft

rigging in combination, a pair of limbs, a connecting thimble having outwardly opening grooves to receive the limbs, and a key for each of said limbs, the limbs and thimble being slotted to receive the keys. 50

4. In a draft yoke for railway car draft rigging in combination, a pair of limbs, a connecting thimble having outwardly opening grooves to receive the limbs and a key 55 for each of said limbs, the limbs having each a slot and a key passing through each slot and engaging the thimble.

5. In a draft yoke for railway car draft rigging in combination, a pair of limbs, 60 means connecting the limbs at one end, a pair of independent lateral plates at the other end and a pair of keys, the plates and limbs having alined slots to receive the keys. 65

6. In a draft yoke for railway car draft rigging in combination, a pair of limbs, means connecting the limbs at one end, a pair of independent plates at the other end and keys, each limb being keyed to the 70 plates.

7. In a draft yoke for railway car draft rigging, the combination with a pair of limbs each of which is slotted transversely, of a plurality of members for detachably 75 connecting the limbs, each of said members being also transversely slotted, and keys passing through the slots of said members and said limbs.

8. In a draft yoke for railway car draft 80 riggings, the combination with a pair of limbs, of a hollow connecting thimble provided with transverse slots at the ends thereof, and a transversely extending key at each end of said thimble passing through 85 said slots and arranged to hold the limbs in engagement with the thimble.

HARRY F. SCHWARTZENBERG.
